US00D847419S

(12) **United States Design Patent** (10) **Patent No.:** **US D847,419 S**
(45) **Date of Patent:** **** Apr. 30, 2019**

(54) **ELECTRONIC VAPING DEVICE**

(71) Applicant: **Altria Client Services LLC**,
Richmond, VA (US)

(72) Inventors: **Eric Hawes**, Richmond, VA (US);
Traci Martin, Richmond, VA (US);
Melissa Burroughs, Richmond, VA (US);
Berina Yerkic-Husejnovic,
Richmond, VA (US); **Raymond Lau**,
Richmond, VA (US); **Christopher S.**
Tucker, Midlothian, VA (US); **Anthony**
Dibitonto, Richmond, VA (US); **Marc**
Sauriol, Richmond, VA (US); **George**
Stafford, Richmond, VA (US); **Jamie**
Nicholson, Richmond, VA (US); **Mark**
Breneman, Richmond, VA (US);
Alistair Bramley, Richmond, VA (US)

(73) Assignee: **ALTRIA CLIENT SERVICES, LLC**,
Richmond, VA (US)

(**) Term: **15 Years**

(21) Appl. No.: **29/545,527**

(22) Filed: **Nov. 13, 2015**

(51) LOC (11) Cl. **27-99**

(52) U.S. Cl.

USPC **D27/194**

(58) **Field of Classification Search**

USPC D27/100, 101, 162-170, 172-195;
D11/146

CPC A24F 1/30; A24F 47/002; A24F 9/14
See application file for complete search history.

CLAIM

The ornamental design for an electronic vaping device, as shown and described.

DESCRIPTION

FIG. 1 is a perspective view of the electronic vaping device; FIG. 2 is another perspective view of the electronic vaping device;

FIG. 3 is a top view of the electronic vaping device

FIG. 4 is a bottom view of the electronic vaping device;

FIG. 5 is a first side view of the electronic vaping device;

FIG. 6 is an opposite side view of the first side view of the electronic vaping device;

FIG. 7 is a front view of the electronic vaping device; and,

FIG. 8 is a rear view of the electronic vaping device.

The broken lines in the drawings depict portions of the electronic vaping device that form no part of the claimed design.

1 Claim, 5 Drawing Sheets
